DESIGN FOR A COMBINATION SOLE AND HEEL

William E. Kavenagh, Windsor, Vt., assignor to
Wingfoot Corporation, Wilmington, Del., a
corporation of Delaware

Application January 5, 1938, Serial No. 74,095

Term of patent 14 years

To all whom it may concern:

Be it known that I, William E. Kavenagh, a citizen of the United States, residing at 38 Ascutney Street, Windsor, in the county of Windsor and State of Vermont, have invented a new, original, and ornamental Design for a Combination Sole and Heel, of which the following is a specification, reference being had to the accompanying drawing, forming part thereof.

Fig. 1 is a plan view of a combination sole and heel showing my new design; and
Fig. 2 is a side elevation thereof.

I claim:

The ornamental design for a combination sole and heel, as shown.

WILLIAM E. KAVENAGH.
